ATOMIZER FOR LIQUIDS

Francisco Salsas-Serra, Paris, France

Application February 26, 1938, Serial No. 192,773
In France March 8, 1937

8 Claims. (Cl. 261—89)

The present invention has for object an atomizer for liquids in which centrifugal force and the effect of dispersion by shock, are combined in a particularly efficient manner whilst limiting to a minimum the rotary parts and by providing for the variation in use of the atomizing conditions. This atomizer is moreover suitable for manufacture in very diverse materials where the gas circulating in the apparatus may be liable to attack certain materials.

The apparatus consists essentially of a rotary part comprising several discs, the highest one of which is solid and the subsequent ones largely apertured towards their centers, and a non rotary concentric member carrying the shock surfaces for the liquid. These two parts can be axially displaced in relation to each other to vary the incident angle of the surfaces of shock and if need be the area of the passage for the gases circulating in the apparatus, which permits of experimentally determining the most favourable relative positions of the two parts for predetermined working conditions that obtain during working, these variations being obtained without dismantling or change of parts.

The discs may have apertured parts with helicoidal or sensibly helicoidal profile in such a manner that the rotation of the discs causes a current of gas in a sensibly axial direction which combines with the other movements of the ambient gas to favour the intimate mixture of the said gas with the particles of liquid still remaining in suspension. This arrangement produces the advantages hereinabove mentioned without in any way diminishing the simplicity of construction and operation of the device.

It is also possible to embody in the apparatus modifications in construction in which:

On the one hand, the discs are disposed in relation to the shock surfaces in such a manner that the less finely divided particles, not carried along by the gaseous current, are reflected in the direction of the solid parts of the discs immediately below where they are subjected to fresh projections up to the last disc which projects the liquid on to a shock surface disposed perpendicularly to the plane of projection which intensifies the bursting effect of the liquid particles;

On the other hand, the feeding of the discs is obtained by lifting the liquid from a reservoir disposed beneath them this lift being obtained by capillarity or by the rotation itself of the shaft carrying the discs. This reservoir receives the non-atomized liquid which runs onto the shock

surfaces and the atomized liquid not carried off by the gaseous current.

The apparatus can also comprise arms for agitating the liquid, flues traversing the upper disc and heating or cooling elements disposed in the path of the gas.

These latter arrangements lend themselves particularly to the construction of an apparatus operating automatically for atomizing in the air or other gas, liquids of most varied nature such as insecticides, bactericides, vaccines and so on or hydrocarbons, either to intensify or accelerate their evaporation, or to disperse in the heart of the gas, liquids which are difficult or impossible to evaporate or liquids of heterogenous composition such as emulsions or liquids containing solid particles in suspension.

The accompanying drawings represent by way of example forms of construction of the invention.

Fig. 1 shows a construction with three discs, 20 with shock surface having fixed incident angle.

Figs. 2 and 3 show modifications in the shock surface with variable incidence.

Fig. 4 shows a form of construction of the disc with helicoidal part.

Fig. 5 shows in section an example of construction of an atomizer with two discs with ascending gaseous current, with lower reservoir for the liquid.

In these figures the same reference numerals indicate the same parts.

In Fig. 1 the shaft 1 rotating at high speed, carries a solid disc 2, and discs 3 and 4 which are largely apertured near their centres. The shock surfaces 2', 3', 4', form a kind of tiered bell 5 arranged exteriorly and concentrically to the shaft 1. The liquid to be atomized arrives at 6 and is distributed over a deflector 7 which allows it to fall at a on the disc 2. It is projected onto 2' and the resultant atomizing is directed towards a' thus passing through the apertures in the lower discs. The parts which are insufficiently divided are collected by the moulding 2'' and fall at b onto the disc 3 which acts in the same manner as the preceding one sending the liquid onto 3' to be atomized in the direction b'. If drops still remain, they collect on the moulding 3'' and fall at c onto the disc 4 which owing to its increased diameter projects them with still greater violence onto the shock surface 4' on which the atomizing is to be completed.

It is quite clear that the number of discs and shock surfaces can be increased or diminished, that is, reduced according to the liquid to be

atomized and the degree of fineness to be obtained.

In Fig. 2 there has been shown a concave shock surface and in Fig. 3 a convex surface which each have the advantage of varying the angle of incidence and consequently the effect of the atomizing action by the simple displacement in an axial direction, of the bell 5 which carries them, or of the spindle carrying the plates.

- 10 In the position shown in full lines the liquid is projected at *d* and atomized in the direction *e* whereas, if the surfaces 2' are brought into the position 2''' (dotted lines) the liquid is projected at *d'* and atomized in the direction *e'*. It will be obvious without having to illustrate it that the generatrices of the shock surfaces could also consist of interrupted lines instead of curved lines.

In Fig. 4 a modification has been shown of the apertured discs 3 or 4 in which the apertures 20 are separated from each other by arms 8 of a sensibly helicoidal form. It will be easily understood that their rotation causes, according to the direction of rotation, a current in an axial upward or downward direction which cooperates 25 with the stirring through the centrifugal current caused by the rotation of the discs.

In Fig. 5 the frame 9 carries a motor 10, the rotor of which is integral with a hollow shaft 11 entering the reservoir for the liquid to be pul- 30 verised or atomized, and marked 12. The hollow shaft 11 carries exteriorly discs 2 and 3 and interiorly a helicoidal part 13 ensuring, upon the rotation of 11, the ascent of the liquid 12 up to the calibrated orifices 14 which allows the 35 liquid to feed or supply the top of the upper plate 2. The air or gas enters the frame 9 through conduits 15, and is forced upwardly by the helically disposed arms 8 of the lower disc 3 and leaves in a direction *f* through the circular 40 passage 16. The liquid is atomized in a direction *a'*, *b'* and the particles not carried along by the air or gas which rises, fall back through the orifices 17 into the liquid reservoir 12.

The apparatus can in addition comprise:

- 45 Arms 18 driven by the hollow shaft 11 for agitating the liquid when the latter has not a homogeneous composition.

On the disc 2, flues 19 through which pass part of the ascending gases, which gives to the whole 50 assembly of the column of gases passing out, a gyroscopic movement favoring its discharge to the exterior at *f'*.

Around the circular conduit 16 a heating or cooling element 20.

55 Finally, as a modification of the arrangements described in reference to Fig. 5, it will be understood without need of illustration, that the helicoidal part 13 can be replaced by a simple wick through which the liquid rises by capillarity in 60 order to reach the orifice 14 (this in the case of a homogeneous liquid of sufficient capillarity), that, on the other hand, the conduit 16 instead of opening into the atmosphere which is ambient, can communicate with a special enclosure 65 to accumulate or distribute in pipes in suitable manner, the gases leaving according to their destination.

Naturally the forms of construction hereinbefore described and shown are given only by way 70 of example and can vary to a large extent without altering the characteristic features of the invention hereinafter claimed.

I claim:

1. An atomizer for liquids comprising in com- 75 bination a rotatable vertical shaft, at least two

discs mounted on said shaft in spaced relation to each other, a stationary hollow body arranged coaxially to said shaft and spaced with respect to the peripheries of said discs, the topmost of said discs being solid, the other discs having a 5 solid peripheral zone and being apertured between said zone and said shaft, means for supplying liquid to the top surface of the topmost disc, means to cause a gaseous medium to pass through said hollow body and said disc apertures, said hollow body having an interior surface widening towards the bottom at least in the portion opposite said topmost disc, said widening surface being so inclined as to reflect liquid particles centrifuged thereupon by said topmost 15 disc substantially on the next lower disc.

2. An atomizer for liquids comprising in combination a rotatable vertical shaft a plurality of discs mounted on said shaft in spaced relation to each other, each disc having a diameter smaller than the subsequent lower disc, the topmost of said discs being solid, the other discs having a solid peripheral zone and being apertured between said zone and said shaft, means for supplying liquid to the top surface of the topmost 20 disc, a stationary hollow body arranged coaxially to said shaft and spaced with respect to the peripheries of said discs, said hollow body being substantially bell-shaped so as to offer inclined inner surfaces opposite the peripheries of said 25 discs, the inclination of said inner surfaces being so selected as to reflect liquid particles centrifuged thereupon by a rotating disc substantially upon the subsequent lower disc.

3. An atomizer as claimed in claim 1, in which 35 each of said discs other than said topmost disc comprises a hub-portion adapted to be attached to said shaft, a solid peripheral zone, and helical blades connecting said hub-portion to said peripheral zone, the width of said peripheral zone 40 being so selected as to catch the major portion of liquid particles reflected from the inclined surface of the hollow body opposite the next higher disc.

4. An atomizer as claimed in claim 1, in which 45 at least one of said discs includes upward directed projections of its solid portion, said projections containing passages in an axial direction.

5. An atomizer as claimed in claim 2 in which the inner surface of said bell-shaped body is 50 stepwise inclined opposite the disc peripheries, each step being provided with a downwardly projecting rim of the pertaining inclined surface, said rim being arranged above the area of the peripheral zone of the next lower disc. 55

6. An atomizer for liquids comprising in combination a rotatable vertical shaft member a plurality of discs mounted on said shaft member in spaced relation to each other, a hollow member encompassing said shaft and said discs coaxially 60 and in spaced relation thereto, means for supplying liquid to the top surface of the topmost disc, means for causing a gaseous medium to pass through said hollow member, said hollow member having at least one inclined interior surface 65 opposite the topmost disc, said inclination being so selected as to reflect liquid particles centrifuged thereupon by said topmost disc on the subsequent lower disc and one of said members being axially shiftable in relation to the other one, 70 whereby the cross-section of the passage of the gaseous medium may be controlled.

7. An atomizer for liquids comprising in combination a rotatable vertical shaft member, a plurality of discs mounted on said shaft member 75

in spaced relation to each other, a hollow member encompassing said shaft and said discs coaxially and in spaced relation thereto means for supplying liquid to the top surface of the top disc, 5 means for causing a gaseous medium to pass through said hollow member, said hollow member having at least one inner surface portion opposite one of said discs and being curved in a vertical cross-section so as to widen towards the bottom, one of said members being axially shiftable 10 relatively to the other one whereby the cross-section of the passage of the gaseous medium and the angle of reflection of liquid centrifuged upon said surface by the disc opposite thereto 15 may be controlled.

8. An atomizer for liquids comprising in combination a rotatable vertical shaft, two discs mounted on said shaft in spaced relation to each other, the diameter of the lower disc being larger 20 than that of the upper disc, said lower disc hav-

ing a solid peripheral zone and an apertured portion between said zone and said shaft, a hollow body arranged coaxial and in spaced relation to the peripheries of said discs, a tank for the liquid to be atomized at the bottom of said hollow body, means for lifting liquid from said tank to the top surface of said topmost disc, means for causing a gaseous medium to pass through said hollow body, the inner surface portion of said hollow body opposite said topmost disc, being 10 inclined so as to widen towards the bottom, the inclination being so selected as to reflect liquid particles centrifuged thereupon by the topmost disc on said lower disc, and the inner portion of said hollow body opposite said lower disc being 15 vertical, so as to cause liquid particles not carried along by the gaseous medium to fall back to said tank.
